UNITED STATES PATENT OFFICE.

MAX SCHEFTEL, OF BROOKLYN, NEW YORK, ASSIGNOR TO GEORGE SCHEFTEL, OF NEW YORK, N. Y.

MONORAIL RAILWAY.

1,034,840.

Specification of Letters Patent.

Patented Aug. 6, 1912.

Application filed May 3, 1911. Serial No. 624,886.

To all whom it may concern:

Be it known that I, MAX SCHEFTEL, a citizen of the United States, and resident of 139 Division avenue, Brooklyn, in the county of 5 Kings and State of New York, have invented certain new and useful Improvements in Monorail Railways, of which the following is a specification.

This invention relates to improvements in 10 monorails and more specifically to means for facilitating the propulsion of cars, locomotives and the like over a single rail.

The leading feature of my invention consists in providing a simple, inexpensive and 15 highly efficient device arranged to move across and be supported on a single rail, and to transport freight at a greater speed than is at present attainable by means of the double rail track.

20 It is a well known fact that cars placed on a single line of wheels will run much faster than if placed on a double rail as at present and it follows that if a car or locomotive can be made to run on a single rail in 25 a normal stable upright position it must necessarily travel faster than the ordinary trains, at the same time using an equal amount of fuel or electricity.

The object of my invention is to provide 30 a new arrangement of a car constructed with the end in view of propelling it on a single rail, the traction power communicated to the wheel mounted on said rail being furnished by horizontal wheels designed 35 to run along the walls of a conduit in the interspace of which the train making up the cars is held vertically disposed at all times. By mounting the rail on the surface of the road bed and causing the horizontal wheels 40 to protrude through the sides of the train and to engage oppositely arranged abutments, it is possible for the cars to move smoothly and speedily along the road bed without losing its equilibrium or stability.

45 With the above and other objects in view my invention consists in the combination, arrangement and details of construction shown in the drawings and then more particularly pointed out in the appended claims.

50 Similar reference characters designate similar parts throughout the several views, wherein,

Figure 1 is a side elevation of a car constructed in accordance with my idea and arranged to be propelled on the usual road 55

bed, being a surface car running on a single rail, Fig. 2 is a side elevation of a car constructed in accordance with my idea and arranged to be propelled in a conduit, Fig. 3 is an end elevation of a car built in accordance with my invention, shown partly in section and partly broken away to disclose the horizontal wheel for imparting motion to a single line of vertical wheels traversing a single rail mounted at the bottom of a conduit, Fig. 4 is an end elevation of a car similar to that shown in Fig. 3 but showing a different species of horizontal wheels, and Fig. 5 is an end elevation of the car shown in Fig. 1.

In the drawings which are merely illustrative of my invention two species of cars will be described arranged to run over a single rail and to be supported thereupon, the cars being provided with traction wheels 75 serving the two-fold function of propelling the vehicle and guiding it in a vertical plane. According to one of the forms of my invention, a conduit 1, five or more yards in width, is to be excavated and smooth 80 walls 2 and 3 formed of any strong material such as concrete or steel, are to be built along its two sides the whole length of the run. The depth of the conduit 1 will be sufficient to accommodate the lower part of 85 my newly constructed car or cars, locomotives, etc., while it is expedient that the upper part or main body of the car project above the surface of the conduit. Upon suitable foundations 4 horizontally disposed 90 and laid along the entire length of the road an ordinary single rail 6 will be mounted, said foundations being preferably embedded in the bottom 5 of the conduit 1, and the wheels of each car are to rest upon 95 and run along the rail.

To cause the cars to move in the conduit with the least resistance from air currents, I have devised a car having a tapering bottom. It will be understood that said car is 100 to consist of two distinct parts, namely, the upper part which is to be built according to the types of the now existing cars, the framework of which is designated 7 and the lower part 8, which is to be specially built 105 or constructed. The lower framework which projects into the conduit will be constructed in length on the shape of a boat, that is in so far as having its floor much narrower than its roof, as shown in the type 110

of cars in Figs. 2, 3 and 4. The sides of the tapering bottom of the car are designated 9 and 10 respectively and terminate in a bottom rectangular portion 11 against the sides of which will be suitably secured the vertically disposed surfaces 12 of brackets 13 and 14 respectively, said brackets having inclined offsets 15 overlying the sides 9 and 10 of the car respectively. For the purpose 10 of reinforcing said brackets they will preferably be ribbed at 16.

From Figs. 1 and 2 it will be noticed that the lower frame 8 of the car is composed of walls which are oppositely arranged, one 15 pair 9 and 10 tapering conformably to the transverse axis of the car and the other 17 and 18 forming the ends of the frame tapering conformably to its longitudinal axis. The brackets 13 and 14 will preferably be 20 disposed at the ends of the bottom portion 11. Any other suitable means may be used to mount the wheels 19 at the bottom of the car, said wheels being preferably formed with two flanges 20 and 21 to obtain better 25 purchase upon the rail 6. Mounted in recesses 22 formed in each bracket are the usual axle boxes 23 engaging coiled springs 24 mounted in said recesses, the axles in said axle boxes being designated 24'. It will be noticed that 30 the wheels 19 will be held by said brackets spaced under and substantially intermediate the edges of the portion 11 thereby causing said wheels under the action of gravity, to take up the concentrated weight of a structure 35 that may effectively be held in equilibrium, and against lateral wobbling.

It is desirable to brace the bottom tapering structure of the car and this may be done by placing gussets 25 at the corners thereof. 40 The car is provided with a compartment 26 in which the driving mechanism is disposed. The bottom or floor of this compartment is designated 27. A rigid tie bar 28 is caused to engage the floor 27 and each of the sides 9 45 and 10 respectively of the tapered structure, as shown in Figs. 3, 4 and 5, the gussets 25 being riveted or otherwise fastened to converging pairs of these bars. Within the compartment 26 and above each and every 50 wheel one or two axles are to be vertically disposed to accommodate a single driving horizontal wheel or two oppositely arranged toothed wheels also horizontally disposed and arranged to operate in the same way to 55 impart motion to the wheels 19.

The width of the car will be smaller than the width of the conduit 1 and owing to the arrangement of the single rail 6 the car may be held in a true vertical position so that the 60 interspaces 29 and 30 are equal at each side thereof. In Fig. 3 a shaft 31 is vertically disposed in bearings 32 and 33 secured respectively to the top and bottom of compartment 26, so as to be in vertical alinement 65 relatively to the wheels 19. On the hub 34,

mounted upon said shaft a traction wheel 35' is rotatably fixed being of a diameter equal to the width of the conduit 1 and protruding through the oppositely alined slots 25 and 36 formed in the sides of the bottom 70 frame 8, so as to be in position to engage the metallic frictional members 37 and 38, at opposite tangential points, said members being secured upon the sides 2 and 3 of the conduit by any suitable means. It will be 75 understood that any number of these wheels may be provided in a train, two being preferably provided and disposed at the ends of each car and that the members 37 and 38 will run continuously co-extensively with 80 the length of the single rail 6, said members being disposed preferably at the upper ends of said walls. These horizontal wheels touching both walls of the conduit will keep the compartment in position and it will 85 neither lean nor fall one way or the other, while in motion or resting, but will be disposed in upright position at all times.

If it is desired to use horizontal toothed wheels in practice two shafts 39 and 40 will 90 be disposed near the ends of the compartment 26, said shafts being mounted in the upper and lower bearings 32 and 33. Rotatably fixed upon each of the shafts and mounted on bosses 41 and 42 are relatively 95 large spur wheels 43 and 44 respectively, each of which protrudes through one of the slots 35 and 36 respectively to engage one of two racks 45 and 46 secured at the upper ends of the walls 2 and 3 of the conduit 1. 100 The spur wheels 43 and 44 do not mesh but are driven clockwise and anti-clockwise, respectively from any suitable motor source, so as to propel the car or train in one and the same direction.

In cities where the building of such excavations are not allowed by law or otherwise, the construction of the cars will be different. The rail 6 will be laid preferably along the center of the street, upon suitable 110 ties and a plurality of oppositely arranged posts 45' and 46' similar in style to the present "elevated road" posts, are to be built, preferably 50 feet apart lengthwise. These posts will be secured to the roadbed by any 115 suitable means, such as brackets 51 and will be just enough apart in breadth to let the car pass through comfortably. These posts, as shown clearly in Fig. 5 are similar to inverted legs of a horseshoe, since the arched portion 52 is arranged to steady said posts at their ends. As an additional means of bracing said posts above the cars the struts 53 and 54 are crossed and secured to each other at an intersecting point and at their 120 ends to the arched portion 52.

The construction of the lower framework of the car is similar to that described but the upper frame work is also similar in 125 general configuration as will be seen upon 130

inspection of Fig. 5. Instead of a lower compartment 26 being formed upon the vehicle an upper compartment 55 is formed carrying the essential driving mechanism at 5 a point above the passenger's compartment. It will be seen that the upper end of the car is formed with longitudinal sides 56 and 57 which taper from large at the bottom to small at the top and ends 58 and 59 which 10 also taper toward the roof so as to give a boat like appearance at the top as well as at the bottom of the car. Either a horizontal friction wheel or two spurwheels may be employed as hereinbefore described, to propel the car and in Fig. 5 the horizontal wheel 35' is shown mounted as already described. It will be understood that in the type of car shown in Fig. 5, the alining slots 35 and 36 will be formed in compartment 55 and the arrangement is such that the traction wheel 35 will keep the car in an upright position and guide it in its horizontal course coöperatively with the single rail 6, and in this way the walls 2 and 3 may be 15 eliminated and the car held against displacement at diametrically opposite points at the top and bottom of the car respectively.

The motive power for driving the traction wheels can be either steam, electric or any other. In case electric power be utilized a third rail will be laid along one of the walls of the canal and as the uses of the third rail are common and understood, no 20 drawings are necessary to illustrate them. The horizontal wheels of the upper part of the car will run along on iron, steel or any other material planks 60 and 61, which will be riveted to the upper sides of the posts and laid along the entire length of the 25 course. When the single traction wheel 35' or each of the oppositely arranged spur wheels 43 and 44 is rotated the frictional engagement of the wheels 19 upon the single rail 6 and of said first named wheels with the steel members 45 and 46, will be such that the car will be sent rapidly forward or rearward according to the direction desired and will be guided in its course by the single rail 6 which must sustain the entire 30 weight and load of the car. The horizontal wheels will make it possible for the cars to move between the walls of the conduit at any desirable speed.

From the above it will be obvious that the monorail system of locomotion is practical, and that the construction of cars and locomotives made in accordance with the principles outlined will adequately meet all conditions of the new system of locomotion.

The mechanical principle upon which my invention is based is simple and is as follows: The power transmitted through an object acting as a lever to another object 45 will not decrease the speed of the object,

and as the object is moved on a single rail its speed must necessarily be increased, a train constructed as above described is practically wedged in between two walls so that it will be impossible for it to run off the track whereby thousands of human lives will be saved. As thus arranged the speed power of the train will be increased and the steadiness of the train will be the same as if there were two lines of rails upon 75 which it stood.

By means of my construction cars may be easily built two or more stories in height thereby making it unnecessary to move many trains. This will cheapen freight 80 rates and passenger rates and will tend to encourage the construction of railroads among the sparsely populated districts and deserts throughout the world. It will also be possible to attain the highest speed without any risk whatsoever, which in the present system of locomotion is a feature of demerit.

Numerous modifications may be resorted to in practice without departing in essence 90 from the invention disclosed.

I claim and desire to secure by Letters Patent:

1. In combination with a conduit, a vehicle of lesser width than said conduit, and having its bottom projecting thereinto, a single rail centrally disposed at the bottom of said conduit, a boat like frame formed at the bottom of said car, oppositely arranged flanged wheels mounted in central alinement 95 at the apex of said frame for engaging said rail, horizontally disposed wheels mounted in said car and projecting through the sides thereof, friction plates disposed at the opposite walls of said conduit and engaged by 100 said last named wheels, and means for causing said last named wheels to move the vehicle in a horizontal course.

2. In combination with a conduit, a car of lesser width thereto and having a boat shaped frame at its bottom projecting into said conduit below its top, wheels disposed in alinement at the bottom of said frame, means for mounting said wheels upon said frame, a single rail engaged by said wheels, 110 and mounted upon the bottom of said conduit, longitudinally extending plates mounted at the top of each wall of said conduit, a compartment formed upon said car above said frame, shafts vertically disposed 115 in said compartments in alinement with said wheels, the sides of said car formed at opposite ends with slots, a relatively large traction wheel mounted on each of said vertical shafts and projecting through a slot at each 120 end of the car to frictionally engage said plates whereby said car is held against wabbling and means for rotating said last named wheels.

3. In combination with a conduit, a car 130

of lesser width thereto and having a boat-shaped frame at its bottom projecting into said conduit below its top, wheels disposed in alinement at the bottom of said frame, 5 means for mounting said wheels upon said frame, a single rail engaged by said wheels and mounted upon the bottom of said conduit, oppositely arranged vertical shafts mounted at each end in said compartment, 10 oppositely arranged slots formed at the opposite ends of the sides of said compartment, longitudinally extending rack bars mounted at the upper ends of the walls of said conduit, spaced apart spur wheels mounted on 15 said oppositely arranged vertical shafts protruding through said slots to engage said rack bars, whereby said car is held against wabbling, means for rotating one of said oppositely arranged wheels clockwise and 20 the other anticlockwise.

4. A device of the character described comprising a plurality of spaced apart upright posts arranged in pairs, friction plates connected to the sides of the posts, a verti-

cal car disposed between said posts, a boat 25 shaped frame formed at the top and bottom of said car, a single rail mounted centrally of said posts, bracket members having inclined portions secured to the sides of the bottom boat shaped frame and having depending portions carrying axles, a flange wheel mounted on each axle and engaging said single rail, a compartment at the upper end of said car, relatively large horizontally disposed wheels frictionally engaging said 30 friction plates to hold said car against wabbling and to impart motion to said first named wheels and means for bracing said posts above the top of the car.

Signed at 139 Division ave., Brooklyn, 40 N. Y., in the county of Kings and State of New York this 28th day of March A. D. 1911.

MAX SCHEFTEL.
